CLAIM

The ornamental design for an exercise band, as shown and described.

DESCRIPTION

FIG. 1 is a frontal perspective view of an exercise band of the present invention; and,

FIG. 2 is a frontal view of the exercise band of FIG. 1. The broken lines shown in FIGS. 1-2 represent unclaimed subject matter and form no part of the claim.

1 Claim, 2 Drawing Sheets

FIG. 1

FIG. 2
